HYDRAULIC TURBINE GOVERNOR

William J. Rheingans, Wauwatosa, Wis., assignor
to Allis-Chalmers Manufacturing Company,
Milwaukee, Wis., a corporation of Delaware

Application March 3, 1941, Serial No. 381,528

12 Claims. (Cl. 253—143)

This invention relates generally to prime mover control systems and particularly to systems controlling a prime mover of the type having adjustable runner vanes.

When the prime mover governed is a hydraulic turbine with adjustable runner vanes, it is necessary to adjust the vanes to a steep angle for producing the maximum torque during starting, and it is necessary to make such adjustment automatically. The control system should therefore provide for setting the runner vanes to a steep angle prior to starting and such setting should be relinquished to the normal vane control mechanism at least as soon as the machine is at its normal operating speed. It is also desirable that means be provided by which the steepness of the runner vane setting may be adjusted, by which the speed at which the runner vane setting will change and by which the time at which the runner vanes will be returned to the normal vane operating mechanism relative to the opening of the fluid flow gate to the turbine may be adjusted.

It is therefore an object of the present invention to provide a control system for a prime mover having adjustable runner vanes in which the runner vanes are caused to assume a steep angular position prior to starting of the prime mover to increase the starting torque thereof and are returned to normal position after the starting operation is completed.

Another object of the invention is to provide a control system for a prime mover having adjustable runner vanes in which system the steepness of setting of the runner vanes prior to starting of the prime mover is adjustable.

Another object of the invention is to provide a control system for a prime mover having adjustable runner vanes in which system the runner vanes are set to a steep position prior to starting of the prime mover and in which the speed at which the runner vane setting is changed to the normal position can be readily varied.

Another object of the invention is to provide a control system for a prime mover having adjustable runner vanes in which system the runner vanes are set to the steep position prior to starting of the prime mover and in which the moment at which the setting of the runner vanes takes place relative to the setting of the gate vanes may be adjusted.

Objects and advantages other than those above set forth will be apparent from the following description when read in connection with the accompanying drawing which diagrammatically il-

lustrates a hydraulic turbine of the adjustable runner vane type having applied thereto an automatic speed control system embodying the means for controlling the steepness of setting, the time for changing the setting, and the rate of change in the setting of the adjustable runner vanes according to the present invention.

The various elements comprising the control system are not shown in their relative positions, their true sizes, nor in their relative proportions, but are shown diagrammatically to more clearly facilitate explanation of the construction and operation of the system.

Referring more particularly to the drawing by characters of reference, the control system is shown as applied to a prime mover such as a hydraulic turbine generally designated at 10 and shown as being of the adjustable propeller type driving an alternating current generator 11 connectable with and disconnectable from the usual power line by conventional switch gear means well known in the art and therefore not shown. The turbine 10 comprises the casing 12 which forms a peripheral water inlet in which are mounted a series of movable vanes 13 forming a gate. The term "gate" is intended to include means other than those disclosed and which may be used for the purpose of controlling and guiding the flow of fluid pressure to any prime mover to which the governing system of the present invention is applied. The gate vanes are mounted on stems 14 journaled at the top and bottom in portions of the casing 12. The upper stem portions extend through the upper portion of the casing to provide for attachment of a conventional linkage connection with a shifting ring 16 which is adapted to be shifted into different positions and to control the positions of the gate vanes and hence to control the flow of fluid to the turbine. The shifting of ring 16 is connected with and actuated by the piston 17 movable within a cylinder 18, the piston and cylinder forming a fluid pressure operated servomotor.

The turbine 10 is connected with the generator 11 by a hollow shaft 19 which is supported against movement relative to its axis by a bearing 21 and on which is mounted the turbine runner comprising a hub 22 from which extend, substantially radially, a series of vanes 23, journaled in suitable bearings in the hub. The inner ends of the vanes 23 are severally provided with trunnions 26 and are connected by linkages 27 with a cross head 28 which is guided to be reciprocated axially of the shaft 19 by an operating rod

29. It will be understood that the positions of the runner vanes relative to each other govern the area of the fluid flow passages for openings between the vanes and that adjustment of the runner vanes increases or decreases the area of the flow passages depending upon the direction of the movement of the vanes. The operating rod 29 extends upwardly through the runner shaft 19 and is fixed to a piston 31 movable within a cylinder 32, the piston and cylinder forming a fluid pressure operated servomotor which is mounted in or is formed as a portion of the runner shaft, preferably adjacent the point where the hollow runner shaft is joined to the hollow generator shaft 33. A tube 34 extends through the hollow generator shaft for the purpose of supplying fluid pressure to the servomotor chamber below the piston 31. A passage 36 about the tube 34, connects with the lower chamber of a distributing head 37 secured to the top of the generator frame and supplies fluid for the downward movement of the piston 31. The tube 34 is fixed to and rotates with the shaft 19 and supplies fluid pressure for the upward movement of the piston 31 by way of an inclined passage 38 through the piston 31 and is provided with perforations 39 in the portion of the tube extending into the upper chamber of the distributing head 37.

Pressure to the runner vane servomotor 31, 32 is controlled by a pilot valve 41 which is governed by a pilot valve operating mechanism including an extension 42 from the piston 17 of the gate operating servomotor 17, 18, connected with an arm 43 fixedly mounted on a rotating shaft 44 and with one arm of a bell crank 45 separately mounted. The shaft 44 has fixedly mounted thereon an arm 46 connected with a rod 47, the other end of which is connected with a cam 48. The cam 48 is in the form of a bell crank mounted on a fixed pivot point 49 and engages a roller 51 mounted on a lever 52 which is pivotally mounted at a fixed point 53 and is biased downwardly at one end by a spring 54 connecting the end of the lever with a fixed point in the control system. The lever 52 is connected by a link 56 with one end of a floating lever 57 to which is connected the stem of the pilot valve 41. Movement of the gate servomotor piston 17 transmits motion through leverage 43, 46 and 47 to the cam 48 from which the motion is transmitted through a second leverage including roller 51, lever 52, link 56 and lever 57 by which the pilot valve 41 is moved to admit fluid pressure from a pipe 58 through pipes 59 or 61 into the pressure head 37. Fluid from the pressure head 37 is also discharged through the pipes 59 or 61 to a discharge pipe 62. The cam 48 provides means for producing a topographic surface by which a different relation may be obtained between the setting of the gate 13 and the positioning of the runner vanes 23. The cam is preferably made of laminated material to facilitate formation of the proper topographic surface thereof after tests have been made with the entire unit in operation in its final setting.

When the gate opening is small and the runner vanes are in a comparatively flat position, the starting torque of an adjustable propeller type turbine is very low. A relatively long period of time is therefore required to bring the turbine up to the speed at which the unit may be connected to the transmission line. Further, with the runner vanes in a relatively flat position, the gate must be opened a relatively large

amount to overcome the starting friction of the prime mover unit. It is then necessary to move the gate quickly in a closing direction to prevent over-speeding of the turbine after rotation has begun. Means are therefore provided herein by which the runner vanes may automatically be initially set in a comparatively steep position and then returned to the desired operating angle and particularly in which the degree of such steep positioning, the speed at which the vanes return to the normal operating angle and the moment, relative to the setting of the gate vanes, at which the runner vanes are returned to the normal operating angle, may be adjusted. The one arm of the cam bell crank 48 is connected at the end thereof with a frame 71 to receive the threaded end of a valve stem 72. The threaded portion of the valve stem 72 is provided with nuts 73 and 74 within and adjacent the ends of the frame 71. The frame 71 cooperating with the nuts 73 and 74 on the valve stem 72 provides a lost motion connection between the cam bell crank 48 and a valve 76. The valve 76 is connected with a source of fluid under pressure by way of a pipe 77 and controls the supply of fluid pressure through a pipe 78 and a needle valve 79 to the cylinder 81 of a servomotor having the piston 82 connected with the end of the lever 52 extending beyond the fixed pivoting point 53 thereof. An adjustable stop 83 extends upwardly through the end of the servomotor cylinder 81, for the purpose of controlling the degree of movement of the servomotor piston 82 and hence the steepness to which the runner vanes may be set. Discharge of the fluid pressure from the servomotor 81, 82 takes place by way of needle valve 79, pipe 78 and valve 76 and a discharge pipe 84. Adjustment of nuts 73, 74 controls the moment in the control system cycle at which pressure is supplied to or may discharge from servomotor 81, 82 and hence controls the moment, relative to the gate setting, at which runner vane control is returned to the normally operating portions of the system. The speed at which the runner vane setting may be changed in either direction is determined by the adjustment of the needle valve 79 which controls the rate of flow of pressure to and from the servomotor 81, 82.

Means must also be provided by which the runner pilot valve 41 is restored to the neutral or mid-position after each operation of the valve in either direction. The restoring movement is derived from the inner shaft tube 34 by way of a rod 86 extending beyond the fluid distributing head 37 and connecting with one arm of a bell crank 87 pivotally mounted at 88. The other arm of the bell crank 87 is connected by way of a rod 89 with the floating lever 57 for the pilot valve 41.

The interconnection of large power generating system in which momentary load fluctuations are relatively small and occur over a relatively large period of time, as compared with the total load, necessitates governing means of extreme sensitivity capable of instant response to the slightest speed variations to maintain adequate distribution stability and proper frequency regulation in the distribution system. Such means are herein shown as comprising a unit including an electric motor connected with and therefore responsive to the frequency (or speed) variations of the prime mover generating unit. The electric motor 91 drives a set of flyballs 92 which controls a servomotor for imparting motion to a floating lever 93 controlling the operation of a

pilot valve 96 which regulates the flow of fluid pressure to the gate operating servomotor 17, 18. The structure of the motor operated so-called flyball head herein only diagrammatically illustrated, is shown in detail in U. S. Patent 2,106,684, issued to J. J. Ring and B. R. Nichols and A. Pfau, on January 25, 1938, and will therefore not be further described. Fluid pressure is supplied to the pilot valve 96 through the pipe 58 and is supplied to the two sides of the servomotor piston 17 by way of pipes 97 and 98. Fluid pressure is discharged from the servomotor through the valve 96 by way of a pipe 99. Any change in the conditions of the distribution line which results in a change of speed of the motor 91 is immediately translated into movement of the flyballs 92 which act on the floating lever 93 to change the setting of the pilot valve 96. The gate operating servomotor 17, 18 therefore immediately commences to vary the opening of the gate 13 to change the flow of fluid to the prime mover 10 dependent on the degree and the sense of the speed change. Floating lever 93 is connected at one end with one end of a lever 101 having its other end connected with the stem of the valve body of the pilot valve 96. The lever 101 is fulcrumed on a nut 102 traveling on a screw 103 which is fixedly mounted and is rotatable either by a hand wheel 104 shown or by other suitable means known.

Movement of the gate servomotor 17, 18, must, however, be interrupted before the effect of decreasing or increasing speed of the prime mover 10 would be apparent in the distribution system and hence would produce a change in the speed of the governor motor 91 to thereby prevent over or under regulation or so-called "hunting" of the unit. Pilot valve 96 must therefore be restored or returned to its neutral or mid-position with a time delay after the operation thereof. Such restoring or compensating means includes the servomotor piston rod extension 42 and the bell crank 45, to one arm of which is connected a rod 106 pivotally connected with the cylinder of a dashpot 107, the structure of which is well known in the art. The piston of the dashpot 107 is connected by a rod 108 with one end of the floating lever 93.

The entire structure is shown in the position assumed by the various elements thereof at standstill in which the gate is closed and the runner vanes are in the steep tilt position. To place the turbine in operation, synchronizing screw 103 is rotated to raise the end of lever 101 connected with pilot valve 96, the other end of the lever 101 being retained in its position by its connection with the movable floating lever 93. The valve body of the pilot valve 96 is raised to permit fluid under pressure to flow through the pipe 97 to the left-hand side of the piston 17 which moves to open the gate 13 and admit fluid under pressure to act on the runner vanes 23. The runner vanes are already in steep tilt position and the fluid acting thereon therefore immediately produces a high torque to start the prime mover generating unit in rotation. Movement of the piston 17, however, rocks bell crank 43 to pull down on rod 106 and the end of the floating lever 93 to raise the end of lever 101 connected with floating lever 93, thus returning lever 101 to the horizontal position which returns the valve 96 to the neutral position shown in the drawing. The above sequence of operations is therefore repeated until the prime mover generating unit is at its full operating speed at which it may be connected

with the transmission line in parallel with other prime mover generating units supplying the line (not shown). When close to full operating speed, the motor 91 and the flyballs 92 assume control 5 of the pilot valve 96, as is well known.

Movement of the piston 17 mentioned above, also moves arm 46 in a counterclockwise direction to push upwardly on rod 47 which rocks the cam bell crank 48 to pull the frame 71 toward the right. The frame 71 moves until the end thereof comes into contact with the nuts 73 and pulls the valve stem 72 of the valve 76 toward the right to shut off the pressure inlet 77 and to open the pipe 78 to the discharge or outlet 84. The spring 54 acting on lever 52 depresses the end of such lever and exerts a lifting force on the piston 82 which forces fluid out of the cylinder 81 through the needle valve 79 until the roller 51 is brought into contact with the surface of the cam 48. 10 Downward movement of the lever 52 and of the rod 56 depresses one end of the floating lever 57 to move the valve body of the valve 41 into position to supply pressure by way of the pipe 59 and the passage 36 to the space above the piston 31. The piston 31 then moves downwardly to turn the runner vanes into a flatter position. 15 Downward movement of the piston 31 pulls the end of the floating lever 87 downwardly to raise the end of the floating lever 57 connected therewith which returns the pilot valve 41 to the mid-position and interrupts the flow of pressure to the servomotor 31, 32. The prime mover generating unit and the control system therefor are now in the normal operating condition in which the 20 flyballs control the action of the gate servomotor 17, 18, and the movement of the runner servomotor 31, 32 is controlled by the position of the cam 48 actuated in response to operation of the gate servomotor 17, 18 to maintain a definite 25 relation between the gate opening and the runner vane position.

Shutdown of the unit requires reversal of the above operations generally, and hence requires lowering of the end of lever 101 to shift valve 96 for admitting pressure to the right hand side of the piston 17 to move gate 13 into the closed position. Movement of the piston 17 toward the left rocks the lever arm 43 to pull down on the rod 47 which rocks the cam bell crank 48 in clockwise direction. Such movement of the cam bell crank 48 pushes on frame 71 until the end of the frame comes into contact with the nut 74 and then moves valve 76 to the position shown at which pressure is admitted by way of the pipe 78 and the valve 79 to the upper side of the servomotor 81, 82. The piston 82 then moves downwardly until it meets the stop 83 and tilts the lever 52 to the position shown. Upward movement of the one end of the lever 52 pulls upwardly on rod 56 to raise one end of the floating lever 57 and to move the valve 41 to the position shown at which pressure is admitted by way of the pipe 61, the tube 39 and the passage 38 to the underside of the piston 31 which rises and rotates the runner vanes 23 into the steep position shown. The gate 13 is now fully closed and the unit is at standstill with the runner vanes in the steepest tilt position in readiness for restarting as above described.

It will thus be seen that the control system provides means for operating the gate 13 responsive to the speed of the prime mover generating unit and which means comprises the motor 91 and the flyball head 92 connected with the 70 pilot valve 96 for controlling the servomotor 17, 75

18 connected with the gate 13 together with the leverage 42, 45, 106 107 and 108 connected with one end of the floating lever 93 for restoring the pilot valve 96 to the neutral or mid-position. The means for adjusting the runner vanes 23 responsive to the action of the gate operating means includes the arm 46 acting by way of the rod 47 on the cam bell crank 48 to raise and lower the end of the lever 52 and the rod 56 connected with the floating lever 51 for actuating the valve 41 which controls the flow of pressure to the servomotor 31, 32 by way of tube 39 and the leverage 87, 88 and 89 for restoring the valve 41 to the mid-position. The servomotor 81, 82 controlled by the valve 76 provides means actuated by the gate operating means for causing a temporary starting of the runner vanes 23 at a steep angle and the action of such temporary setting control means is modified by the frame 71 and the nuts 73 and 74 on the valve stem 72 which form an adjustable lost motion connection for controlling the moment in the cycle of operation of the gate operating means at which the steep setting control means becomes effective and ineffective. Adjustment of the needle valve 79 provides means for adjusting the rate of fluid supply to the servomotor 81, 82 and therefore provides means for adjusting speed of movement of the vane steep setting control means. The stop 83 limits the movement of the servomotor piston 82 in the steep setting direction and thus provides means for controlling the degree of movement of the steep setting control means.

Although but one embodiment of the present invention has been illustrated and described, it will be apparent to those skilled in the art that various changes and modifications may be made therein without departing from the spirit of the invention or from the scope of the appended claims.

It is claimed and desired to secure by Letters Patent:

1. In a control system for a prime mover having a gate controlling the flow of fluid pressure thereto and having a runner with adjustable vanes, means for operating the gate responsive to the speed of the prime mover, means for adjusting the runner vanes responsive to actuation of said gate operating means, a fluid pressure operated servomotor for causing the temporary setting of the runner vanes at a steep angle, a valve actuated by said gate operating means for controlling the flow of pressure to said servomotor, and adjustable means actuated by said gate operating means for controlling said valve to vary the moment in the cycle of said gate operating means of actuation of said servomotor.

2. In a control system for a prime mover having a gate controlling flow of fluid pressure thereto and having a runner with adjustable vanes, means for operating the gate responsive to the speed of the prime mover, means for adjusting the runner vanes responsive to actuation of said gate operating means, a fluid pressure operated servomotor for causing the temporary setting of the runner vanes at a steep angle, a valve actuated by said gate operating means for controlling the flow of pressure to said servomotor, an adjustable lost motion connection between said gate operating means and said valve and means for adjusting said lost motion connection to vary the moment in the cycle of said gate operating means of actuation of said servomotor.

3. In a control system for a prime mover hav-

ing a gate controlling the flow of fluid pressure thereto and having a runner with adjustable vanes, means for operating the gate responsive to the speed of the prime mover, means for adjusting the runner vanes responsive to actuation of said gate operating means, means actuated by said gate operating means for causing the temporary setting of the runner vanes at a steep angle, and means for adjusting the speed of movement of said vane steep setting means.

4. In a control system for a prime mover having a gate controlling the flow of fluid pressure thereto and having a runner with adjustable vanes, means for operating the gate responsive to the speed of the prime mover, means for adjusting the runner vanes responsive to actuation of said gate operating means, a servomotor actuated by said gate operating means for causing the temporary setting of the runner vanes at a steep angle, and means for adjusting the speed of movement of said servomotor.

5. In a control system for a prime mover having a gate controlling the flow of fluid pressure thereto and having a runner with adjustable vanes, means for operating the gate responsive to the speed of the prime mover, means for adjusting the runner vanes responsive to actuation of said gate operating means, a fluid pressure operated servomotor actuated by said gate operating means for causing the temporary setting of the runner vanes at a steep angle, and a valve for adjusting the rate of flow of pressure to said servomotor for controlling the speed of movement thereof.

35 6. In a control system for a prime mover having a gate controlling the flow of fluid pressure thereto and having a runner with adjustable vanes, means for operating the gate responsive to the speed of the prime mover, means for adjusting the runner vanes responsive to actuation of said gate operating means, means actuated by said gate operating means for causing the temporary setting of the runner vanes at a steep angle, and means for controlling the degree of movement of said vane steep setting causing means.

40 7. In a control system for a prime mover having a gate controlling the flow of fluid pressure thereto and having a runner with adjustable vanes, means for operating the gate responsive to the speed of the prime mover, means for adjusting the runner vanes responsive to actuation of said gate operating means, a servomotor actuated by said gate operating means for causing the temporary setting of the runner vanes at a steep angle, and means for controlling the degree of movement of said servomotor to limit the steepness of setting of the runner vanes.

45 8. In a control system for a prime mover having a gate controlling the flow of fluid pressure thereto and having a runner with adjustable vanes, means for operating the gate responsive to the speed of the prime mover, means for adjusting the runner vanes responsive to actuation of said gate operating means, means actuated by said gate operating means for causing the temporary setting of the runner vanes at a steep angle, and a stop for controlling the degree of movement of said vane steep setting causing means to limit the steepness of setting of the runner vanes.

50 9. In a control system for a prime mover having a gate controlling the flow of fluid pressure thereto and having a runner with adjustable vanes, means for operating the gate responsive

70

to the speed of the prime mover, means for adjusting the runner vanes responsive to actuation of said gate operating means, a servomotor actuated by said gate operating means for causing the temporary setting of the runner vanes at a steep angle, and a stop for controlling the degree of movement of said servomotor to limit the steepness of setting of the runner vanes.

10. In a control system for a prime mover having a gate controlling the flow of fluid pressure thereto and having a runner with adjustable vanes, means for operating the gate responsive to the speed of the prime mover, means for adjusting the runner vanes responsive to actuation of said gate operating means, a fluid pressure operated servomotor for causing the temporary setting of the runner vanes at a steep angle, a valve actuated by said gate operating means for controlling the flow of pressure to said servomotor, and a valve arranged between said servomotor and the first said valve to adjust the rate of flow of pressure to said servomotor for controlling the speed of movement thereof.

11. In a control system for a prime mover having a gate controlling the flow of fluid pressure thereto and having a runner with adjustable vanes, means for operating the gate responsive to the speed of the prime mover, means for adjusting the runner vanes responsive to actuation of said gate operating means, a fluid pressure operated servomotor for causing the temporary setting of the runner vanes at a steep angle, a valve actuated by said gate operating

means for controlling the flow of pressure to said servomotor, an adjustable lost motion connection between said gate operating means and said valve, means for adjusting said lost motion connection to vary the moment in the cycle of said gate operating means of actuation of said servomotor, and a stop for controlling the degree of movement of said servomotor to limit the steepness of setting of the runner vanes.

12. In a control system for a prime mover having a gate controlling the flow of fluid pressure thereto and having a runner with adjustable vanes, means for operating the gate responsive to the speed of the prime mover, means for adjusting the runner vanes responsive to actuation of said gate operating means, a fluid pressure operated servomotor for causing the temporary setting of the runner vanes at a steep angle, a valve actuated by said gate operating means for controlling the flow of pressure to said servomotor, an adjustable lost motion connection between said gate operating means and said valve, means for adjusting said lost motion connection to vary the moment in the cycle of said gate operating means of actuation of said servomotor, a stop for controlling the degree of movement of said servomotor to limit the steepness of setting of the runner vanes, and a valve arranged between said servomotor and the first said valve to adjust the rate of flow of pressure to said servomotor for controlling the speed of movement thereof.

WILLIAM J. RHEINGANS.
